AUTOMATIC WATER CONTROL SWITCH

Earl J. Sourber, Allentown, Pa.

Application October 18, 1948, Serial No. 55,169

7 Claims. (Cl. 200—81.9)

1

This invention relates to automatic water controls and is concerned primarily with a control designed for use with an air compressor, water cooled bearing, ammonia compressor, and the like.

In the operation of a present day apparatus of this type, the flow of water is an element highly essential to the operation because it is needed for cooling purposes. If the flow of water should, for any reason, be discontinued or fall below a predetermined minimum, the mechanism should be shut down otherwise there would be a likelihood of serious damage to the machine.

With the above noted condition in mind, the present invention has in view as its foremost objective, the provision of a control mechanism which is particularly designed for use in conjunction with an air compressor or similar mechanism as above noted and which is responsive to the flow of water so that if the latter should fall below a predetermined minimum, the operation of the compressor will either be automatically discontinued, or a signal, either audible or visible, will be rendered effective.

In providing a device of this type for use with an air compressor, it is highly desirable that the mechanism be susceptible to adjustment so that the minimum flow of water which determines when the compressor is to be shut down may be varied.

Thus, another highly important object of the invention, is the provision, in a control mechanism of the type indicated, of means for varying the point at which the control mechanism shuts down the compressor or indicates that the operation should be discontinued.

In providing a device of this type, it is important that the mechanism be as simple as possible to provide surety of operation. Thus, another object is to provide an automatic control of the type indicated, which is highly simplified, and yet includes the feature of adjustability which is so important.

In carrying out the above noted ideas in a practical embodiment, a fitting is employed which is adapted to be included in the flow of water that is the controlling element. This fitting provides a conduit through which the water passes, and pivotally mounted in a wall thereof is a vane which is subject to the flow of water. Extending outwardly of the fitting from the shaft on which the vane is mounted is an arm that carries a weight at its free end. This weight normally is counterbalanced by the flow of water through the fitting.

Pivotally mounted on the exterior of the fitting is a platform which in turn carries a pair of complementary contacts. One of these contacts

2

is mounted on a spring arm which normally maintains it in engagement with the other contact. However, when the flow of water through the fitting falls off sufficiently to destroy the counterbalance of the weighted arm, the latter falls under gravity action and engages the spring arm to break the contacts.

These contacts are included in an electrical circuit which may also include either a signal or a relay which will be effective to discontinue the operation of the compressor.

Another important object of the invention is the provision, in control mechanism of the character aforesaid, of means for adjusting the position of the platform whereby the point at which the weight engages the spring arm may be varied. This means preferably takes the form of a set screw that is associated with the pivotal mounting of the platform.

20 Various other more detailed objects and advantages of the invention such as arise in connection with carrying out the above noted ideas in a practical embodiment will in part become apparent, and in part be hereinafter stated as 25 the description of the invention proceeds.

The invention, therefore, comprises an automatic control designed for use in conjunction with an air compressor to be affected by the flow of water thereto, and which consists es-

30 sentially of a fitting in which a vane is pivotally mounted and counterbalanced by a weight. A pair of normally engaged contacts are adapted to be affected by said weight to break the engagement when the flow of water falls below a 35 predetermined minimum. Means in the form of an adjustable platform, which carries the contacts, is provided for adjusting the point at which the contacts are broken.

For a full and more complete understanding 40 of the invention, reference may be had to the following description and accompanying drawing wherein:

Figure 1 is a front elevational view of control mechanism as included in the line which provides the flow of water to an air compressor.

Figure 2 is a vertical section through the fitting.

Figure 3 is a horizontal section taken about on the plane represented by the line 3—3 of 50 Figure 1, and shows the platform and mechanism associated therewith in plan, and

Figure 4 is a detailed elevation of the platform and mechanism associated therewith, and is taken in the direction of the arrows 4—4 of 55 Figure 1.

Referring now to the drawing wherein like reference characters denote corresponding parts, and first more particularly to Figure 1, a drain is

represented diagrammatically at 10. A conduit indicated at 11 is shown as leading into the drain 10 for the purpose of eliminating water which is used in cooling the operating parts of a compressor. Another conduit 12 communicates with a compressor (not illustrated). The end of this pipe or conduit is flanged as represented at 13. Another conduit 13 carries a flange 15, and between the conduits 14 and 11, there is an inverted funnel arrangement 15, which provides transparent panels at 16 which afford visibility so that one may tell at a glance whether or not water is flowing through the compressor. Between the flanges 13 and 15 of the contacts 12 and 14 respectively is a fitting F which carries the control mechanism of this invention.

Upon referring more particularly to Figure 2, it will be noted that the fitting F includes a tubular pipe section 17 having flanges 18 and 19 at the opposite ends and providing a bore 20. The flange 18 is complementary to the flange 13 with which it engages and headed screws represented at 21 pass through aligned openings in the flanges 13 and 18 to establish the connection of the fitting F to the conduit 12. In a similar manner, the flange 19 engages the flange 15, and additional headed screws 21 establish the connection to the conduit 14. Extending into the bore 20 is a ring-like spout 22 that is integrally joined to the pipe section 17, and which presents an end face at 23 that is inclined with respect to the axis of the bore 20. One wall of the pipe section 17 is cut away to provide a recess at 24, and the fitting F on the side of the pipe section 17 is enlarged to provide a substantially flat face 25.

A plate 26 is fitted over this face 25 and if it is desired, a fluid-tight packing such as the gasket shown at 27 may be interposed between the plate 26 and face 25. The inner face of the plate 26 is cut away to provide a recess at 28 which constitutes in effect a continuation of recess 24.

Referring now more particularly to Figure 3, it will be seen that the face 25 is formed with a semi-cylindrical socket on each side of the recess 24. These semi-cylindrical sockets are designated 29. Likewise, the inner face of the plate 26 is formed with semi-cylindrical sockets 30, one being on each side of the recess 28. These sockets 29 and 30 on the opposite sides of the recess 24-28 provide bearings for a shaft 31, which is positioned therein. Drivably connected to this shaft 31, in any preferred manner, is a sleeve 32. Extending inwardly across the recess 24 to the bore 20 from this sleeve 32 is an arm 33, which carries at its free end a vane 34 that is adapted to engage the face 23 of the ring-like spout 22 which limits the movement of the vane 34.

As shown more clearly in Figure 3, the shaft 31 is continued beyond the edge of the plate 26 at one side and bent outwardly to provide an arm 35 that is integrally joined to the shaft 31. The free end of this arm 35 carries a weight 36 of appropriate size.

The outer face of the plate 26 carries a bracket 37 which may be secured thereto in any preferred manner as by being cast integrally therewith, welding or soldering. At each end of the bracket 37, there is an ear 38. A table or platform 39 has side flanges 40 and 41. These side flanges overlie the ears 38 and a pivot pin 9 extends through aligned openings in the ears 38, and flanges 41 and 40 respectively. These pivot pins serve to pivotally mount the table 39 on the plate 26.

At the lower inner corner of the side flanges 41, there is a tab 42 of sufficient thickness to pro-

vide a threaded opening into which is screwed a screw stem 43, the outer end of which carries a knurled operating member 44. The inner end of the screw stem 43 engages the plate 26. It is evident that the operating member 44 may be availed of to adjust the angular relation between the table 39 and the plate 26. The side flange 40 is continued out beyond the outer edge of the table 39 to provide an extension 45 which carries a pair of spaced ears 46. Pivotally mounted on these ears 46 by a pin 47 is a contact carrier 48. A tension coil spring 49 has one end secured to the end of the carrier 48 as indicated at 50 while its other end is anchored to a tab 51 that extends outwardly from the lower edge of the extension 45. The normal tendency of this spring 49 is to rotate the carrier 48 in a counterclockwise direction (speaking with reference to the showing of Figure 4).

20 The side flange 41 is also continued out beyond the edge of the table 39 and turned outwardly as represented at 52 to provide a stop for limiting movement of the carrier 48 in a clockwise direction.

25 Mounted on the carrier 48 is a screw 53. A small plate 55 is conductively connected to the screw 53 and mounted thereon is a contact 56. A cable 54 is connected to the end of the plate 53. A binding post 57 is mounted on the table 39, and 30 a cable 58 is connected thereto. A plate 59 is connected to this binding post 58 and carries a contact 60 that is disposed immediately above the contact 56. These contacts 56 and 60 are normally maintained in engagement by the 35 spring 49, but the engagement is broken when the weight 36 strikes the outer end of the carrier 48 to move it downwardly against the influence of the spring 49.

40 The cables 54 and 58 are included in a circuit which also includes either a relay (not illustrated) which would operate a switch to automatically discontinue operation of the compressor 10 and/or a signal either audible or visible such as a light or alarm.

Operation

While the operation of the above described mechanism is believed to be obvious, it may be briefly outlined by noting that as water flows through the conduit 12 from the compressor 10 it passes through pipe section 17 of the fitting F. This flow of water takes place under gravity action and affects the vane 34 so as to maintain the latter in a downwardly depressed position whereby the weight 36 at the end of the arm 35 is kept in an upwardly raised position off of the carrier 48. This permits the spring 49 to maintain the engagement of the contacts 56 and 60. Thus, the circuit which is controlled by these contacts is maintained complete.

60 When the flow of water through the pipe section 17 falls below a predetermined minimum, the weight 36 will fall downwardly under gravity action as it is no longer counterbalanced by the flow of water. As it strikes the outer end of the carrier 48, the contact 56 is moved downwardly to break the engagement of the contacts and interrupt the circuit. Thus the relay is set in operation to shut down the compressor 10 or an appropriate signal is set off. If desired the automatic discontinuance of the operation may be accompanied by one or both of the signals.

65 It is important to note that the point at which the contacts 56 and 60 are broken depends upon the angular position of the table 39, and that the

latter is adjustable through the medium of the set screw 43. Thus, the mechanism is adapted for adjustment to any particular volume in the flow of water which is desired.

While a preferred specific embodiment of the invention is hereinbefore set forth, it is to be clearly understood that the invention is not to be limited to the exact constructions, mechanisms, and devices illustrated and described because various modifications of these details may be provided in putting the invention into practice within the purview of the appended claims.

What is claimed is:

1. In control mechanism of the character described, the combination of: a fitting having a pipe section formed with a bore that is adapted to assume a vertical position as it is mounted in a line through which water flows, a shaft rotatably mounted in said fitting, a vane extending into the said bore and drivably connected to said shaft about which it is adapted to swing as an axis, an arm carried by said shaft and extending outwardly of said fitting in a direction substantially normal to said pipe section, a weight on said arm, a pair of relatively movable contacts included in a control circuit, and a carrier on which one of said contacts is mounted, said carrier being adapted to be engaged by said arm to break said contacts.

2. In control mechanism of the character described, the combination of: a fitting having a pipe section formed with a bore that is adapted to assume a vertical position as it is mounted in a line through which water flows, a shaft rotatably mounted in said fitting, a vane extending into the said bore and drivably connected to said shaft about which it is adapted to swing as an axis, an arm carried by said shaft and extending outwardly of said fitting in a direction substantially normal to said pipe section, a weight on said arm, a table extending outwardly from said fitting, a spring biased carrier mounted on said table, a contact on said carrier and a complementary contact on said table, said contacts being adapted to be included in a control circuit, said carrier being positioned beneath said weighted arm whereby it is adapted to be engaged thereby to break said contacts.

3. In control mechanism of the character described, the combination of: a fitting having a pipe section formed with a bore that is adapted to assume a vertical position as it is mounted in a line through which water flows, a shaft rotatably mounted in said fitting, a vane extending into the said bore and drivably connected to said shaft, an arm carried by said shaft and extending outwardly of said fitting, a weight on said arm, a table extending outwardly from said fitting, a spring biased carrier mounted on said table, a contact on said carrier and a complementary contact on said table, said contacts being adapted to be included in a control circuit, said carrier being positioned beneath said weighted arm whereby it is adapted to be engaged thereby to break said contacts, and means for adjusting the said table relative to said platform whereby the point at which said contacts are engaged by said weighted arm is varied.

4. In control mechanism of the character described, the combination of: a fitting having a pipe section formed with a bore extending therethrough, a shaft pivotally mounted in said fitting, a vane drivably connected to said shaft and positioned in said bore, an arm drivably connected to said shaft and extending outwardly of said

fitting in a direction substantially opposite to said vane, a weight on said arm, a table pivotally mounted on said fitting at the side from which said arm extends, means for adjusting the angular relation of said table to said fitting, a carrier pivotally mounted on said table, a contact on said carrier, and spring means associated with said carrier urging said contacts into engagement, a portion of said carrier being located beneath said weighted arm whereby it is adapted to be engaged thereby to break said contacts.

5. In control mechanism of the character described, the combination of: a fitting having a pipe section formed with a bore extending therethrough, a shaft pivotally mounted in said fitting, a vane drivably connected to said shaft and positioned in said bore, means in said bore adapted to be engaged by said vane to limit movement thereof, an arm drivably connected to said shaft and extending outwardly of said fitting in a direction substantially opposite to said vane, a weight on said arm, a table pivotally mounted on said fitting at the side from which said arm extends, means for adjusting the angular relation of said table to said fitting, a carrier pivotally mounted on said table, a contact on said carrier, and spring means associated with said carrier urging said contacts into engagement, a portion of said carrier being located beneath said weighted arm whereby it is adapted to be engaged thereby to break said contacts.

6. In control mechanism of the character described, the combination of: a device for adjustably mounting a pair of contacts on a fitting, said device comprising a table, means on said table for pivotally mounting the same on a fitting, a set screw carried by said table and having a free end adapted to engage said fitting to determine the angular position of said table relative thereto, a contact carrier pivotally mounted on said table, a contact on said table, a complementary contact on said carrier, and a spring biasing said carrier to urge said contacts into engagement.

7. In control mechanism of the character described, the combination of: a fitting adapted to be mounted in a vertical position and having a bore through which water is adapted to flow, said fitting being formed with a flat face, a plate detachably secured to said face, said plate and said face being formed with semi-cylindrical sockets defining bearings, a shaft rotatably mounted in said bearings, a vane drivably connected to said shaft and positioned in said conduit, said vane being swingable on said shaft as an axis, an arm drivably connected to said shaft and extending outwardly of said fitting in a direction substantially opposite to said vane, a weight on said arm, and a contact assembly adapted to be engaged by said weighted arm to break said contacts.
